UNITED STATES PATENT OFFICE.

FRED M. CARROLL, OF DAYTON, OHIO, ASSIGNOR TO THE NATIONAL CASH REGISTER COMPANY, OF DAYTON, OHIO, A CORPORATION OF OHIO, (INCORPORATED IN 1906.)

ACCOUNTING AND CHECK-DELIVERING MECHANISM.

1,186,546.

Specification of Letters Patent.

Patented June 13, 1916.

Application filed September 11, 1913. Serial No. 789,303.

To all whom it may concern:

Be it known that I, FRED M. CARROLL, a citizen of the United States, residing at Dayton, in the county of Montgomery and 5 State of Ohio, have invented certain new and useful Improvements in Accounting and Check-Delivering Mechanism, of which I declare the following to be a full, clear, and exact description.

10 In application for Letters Patent of the United States No. 773,943, filed June 16, 1913, by the present applicant there is shown a machine designed primarily for use in large commercial establishments, such as department stores, which machine is arranged 15 to print upon a sales slip symbols designating the cashier operating the machine, the consecutive number of the sale, the date and the amount of the transaction. This machine is also provided with a record strip 20 upon which is recorded the same information which is recorded upon the sales slip and in addition thereto has characters perforated therein symbolical of the amount of 25 the transaction, the number of the clerk making the sale and the department in which the clerk is employed.

It is the principal object of this invention 30 to provide mechanism for severing the record strip into checks and to distribute the severed checks among a plurality of receptacles each of which is divided into a plurality of compartments, which compartments are assigned to the various clerks operating 35 under a cashier and which are selected under control of clerks' manipulative devices of the cashier's machine. By the assorting of these checks in the clerks' compartments the total 40 of the clerks' sales may be ascertained readily by simply adding up the checks of each compartment. This adding of the clerks' checks may be accomplished in a number of different ways. For instance, the perforations in the checks may control registering 45 mechanism, or in case the checks are not perforated but simply have the amounts recorded thereon the totals of the checks in the various compartments may be accumulated upon an adding machine. Heretofore in order 50 to tabulate the clerks' and department totals it has been necessary to assort the sales slips according to the clerks making the transactions and then tabulate the clerks' totals, from which totals the departmental

totals may be ascertained by the adding of 55 the various clerks' totals operating in any department. With this improved machine it will be obvious that this burdensome work of assorting the sales slips is entirely eliminated as the checks bearing date similar to 60 that recorded upon the sales slip are automatically assorted by the machine.

To record, perforate, sever the check, and to distribute it among the various compartments during a single operation would tend 65 to speed up the parts for performing these various functions with the result that in a short while some of the parts would likely become worn or defective in some respects with the inevitable consequence of making 70 the machine go wrong, and it is a further object of this invention to have these various parts coöperate in such a manner that different functions are performed upon different cycles of operations of the machine, and as 75 shown herein the printing and perforating of the check is accomplished during the first cycle of operation of the machine, the severing of the check occurring upon the second cycle of operation and the delivering 80 of the check occurring upon the third cycle of operation of the machine, it being understood that during the recording and perforating of the checks during the first cycle of operation of the machine manipulative 85 devices are also set up for controlling the delivering of the check into its proper receptacle and compartment upon the third cycle of operation of the machine. By thus extending the functions performed by the 90 machine over several cycles of operation none of the parts attain an abnormal speed and consequently the wear on said parts is reduced to a minimum.

With these and incidental objects in view, 95 the invention consists in certain novel features of construction and combinations of parts the essential elements of which are set forth in appended claims, and a preferred form of embodiment of which is hereinafter 100 described with reference to the drawings which accompany and form part of this specification.

Of said drawings: Figure 1 is a perspective view of the upper portion of the machine. Figs. 2, 3 and 4 are side elevations partly in section of the right hand side of 105 the machine. Fig. 5 is a rear elevation of

the transverse shafts and connecting devices for setting the selecting mechanism for the punches. Fig. 6 is a top plan view of the connecting devices for setting the selecting mechanism for the punches. Fig. 7 is a sectional view of the frame carrying the punches and the slides for selecting the punches. Fig. 8 is a detail view of the feeding devices for the check strip. Figs. 9 and 10 together constitute enlarged views of the front half of the mechanism for controlling the delivering of the checks to the various receptacles and compartments. Fig. 11 is a detail view of the latching detent for the slides which operate the deflecting plates of the check compartments. Fig. 12 is a detail view of the locking ring for the receptacle selecting device. Figs. 13 and 14 together constitute a top plan view of the check receptacle and compartment selecting mechanism. Fig. 15 is a view taken on line 15-15 of Fig. 14 and looking in the direction of the arrow. Fig. 16 is a partial rear elevation of the check severing mechanism and co-operating devices. Fig. 17 is a perspective view of the upper part of the check hopper. Fig. 18 is a detail view of the operating mechanism for the check severing device. Fig. 19 is a detail view of the cams for operating the mechanism for selecting the receptacle in which the check is to be deposited and for locking the check depositing mechanism. Fig. 20 is a detail view of the cams for locking the check receptacle selecting mechanism in its adjusted position and for restoring the check receptacle selecting mechanism to its normal position. Fig. 21 is a top plan view of the check gripping and delivering mechanism. Fig. 22 is a side elevation of Fig. 21. Fig. 23 is a detail view of the lower portion of the check hopper in which the check comes to rest prior to being gripped and delivered to its proper compartment of the receptacle. Fig. 24 is a plan view of one of the severed checks with the appropriate data recorded and perforated thereon.

The system commonly employed in department stores is one in which a plurality of departments are assigned to a cashier, each of which departments has a number of clerks operating therein. As each clerk makes a sale she forwards a sales slip to the cashier having supervision over her department and the cashier sets up in the cash register manipulative devices corresponding to the total of the sale and the class of sale as well as manipulative devices designating the clerk and the department. After setting up these various manipulative devices the machine is operated and data corresponding to the manipulative devices is recorded upon the sales slip and also upon a record strip contained in the machine, after which a portion of the sales slip con-

taining the printed record is wrapped with the goods and returned to the clerk making the sale, who in turn hands the package to the customer.

In order that the detail description which is to follow may be better understood, a general description of the functions performed by the improved machine and the mode of operation thereof will be here given.

The machine herein shown is provided with a bank of special keys such as "C. O. D.", "cash", and "credit", five banks of amount keys, and also with five banks of keys for setting up a composite number, the first two banks of the latter keys reading from the left, Fig. 1, representing the station in which the machine is located, the third bank the departments assigned to a particular cashier, and the fourth and fifth banks the clerks operating in these various departments. A foreign key having the caption "F" is provided, which key is operated by the cashier when a clerk other than those assigned to the cashier, makes a sale in any one of the departments over which that particular cashier has charge. These various keys determine the extent of movement imparted to differential mechanism which is actuated upon the operation of the crank handle. The machine herein shown is provided with two totalizers upon one of which all the cash transactions made by the clerks operating under a particular cashier are accumulated, while the other totalizer is used for the purpose of accumulating the "cash" sales made by foreign clerks or those not operating under this particular cashier. When transactions other than "cash", such as "C. O. D.", and "credit" transactions are recorded no entries of such transactions are made upon the totalizers but they are recorded on the sales slips and record strip.

The differential mechanism controlled by the various manipulative devices above described are connected to type carriers for recording upon a record strip the kind of transaction, the amount of same, and a composite number representing the station, the clerk and the department in which the sale is made. A cashier's symbol is also set up by the cashier operating the machine, there being provided in this particular machine two of such symbols, one of which has to be in position for the purpose of printing upon the record strip and also upon the sales slip before the machine can be manipulated. In addition to printing the above data upon the record strip the consecutive number of the sale and the data thereof is also recorded upon said strip. The sales slip is arranged to have printed thereupon in triplicate the cashier's symbol, the consecutive number of the sale, the data

thereof and the amount. One of these impressions is taken upon the original of the said slip while the remaining two are taken upon the duplicate and the latter severed between said impressions and the severed portion deposited in one of two receptacles depending upon whether the transaction is made by a regular clerk or a foreign clerk.

The transaction and the amount manipulative devices as well as the department and clerks' manipulative devices control devices for selecting punches which perforate the record strip with characters identifying the transaction, the amount thereof, and the clerk by whom the transaction is made, and the department in which it is made, these perforations being used for the purpose of controlling subsequent accounting operations as hereinafter described.

Mechanism is provided for severing the record strip into checks, each check bearing the recorded and perforated data pertaining to a particular transaction. These checks after being severed are automatically distributed to a plurality of receptacles each one having a series of compartments, the selection of the receptacles and compartments being under the control of the clerks' manipulative devices. By this automatic assorting of the checks it will be obvious that at the end of the day totals of the sales made by the various clerks under a cashier may be ascertained quickly, whereas heretofore it has been necessary, in order to obtain the clerks' totals, to assort manually the sales slip after the same has been received from the various stations throughout the store, which assortment in itself requires a considerable amount of time and labor.

As previously mentioned, this machine is provided with a plurality of banks of keys or manipulative devices comprising one bank of special transaction keys 1, such as "C.O.D.", "cash" and "credit;" five banks of amount keys 2 and five other banks of keys consisting of two banks of clerks' keys 3, one bank of department keys 4 and two banks of keys 5 representing the various stations, these last five mentioned banks of keys when taken collectively representing a composite number. A foreign key 6 having the caption "F" is also provided which key is used by the cashier when a clerk other than those assigned to the cashier makes a sale in one of the departments over which the cashier has supervision. The special transaction keys 1 control the release of an operating handle 600 in a manner fully shown and described in the aforementioned application and which it is thought not necessary to illustrate here as it forms no part of the present invention. This operating handle 600 is provided with a pinion 7 Fig. 2 which meshes with a gear 8

secured to a shaft 9 extending through the machine and this gear 8 meshes with a similar gear 10 secured to a stub shaft 11 projecting from the frame work 12 of the machine. Secured to the shaft 9 to which is also secured the gear 8 as previously mentioned, is a disk 12^a which is provided with a cam groove 13. In this cam groove projects a roller 14 extending from the upper end of a vertical member of a bell crank 15 which is pivoted as at 16 on the right hand side frame 12. The horizontal arm of the bell crank is connected by a link 17 to an arm 18 secured to a transverse shaft 19. Extending downwardly from each end of the shaft 19 is an arm 20, which arms are connected at their lower ends by cross rod 21. A series of driving elements 22, one for each bank of keys, are connected to the rod at their forward ends and at their rearward ends are supported by links 23 pivotally mounted as at 24 to their respective frames 25 which support the various banks of keys. From this brief description it will be seen that as the cam disk 12 is rotated in an anti-clockwise direction, Fig. 2, the bell crank 15 will first be oscillated in a clockwise direction and then back to normal position, by which movement, through link 17 and arm 18, the frame comprising the side arms 20 and cross rod 21 will be rocked first in an anti-clockwise direction and then in a clockwise direction. This movement of the frame, which is a constant one, will be imparted to the driving elements 22 connected to the cross rod 21 of said frame at their forward ends.

Coöperating with each bank of keys is a series of levers 26, the lower end of said levers being connected by a slot and pin connection 27 and 28 with their respective driving element 22. The upper end of the levers 26 are normally free while at the intermediate point between their ends each lever of a particular bank is pivoted to a driven member 29. The forward end of each of the latter members is guided by a lug 30 projecting from its respective key frame 25 while the rear end of said driven member is connected to the upper end of an arm 31 loosely mounted upon the foremost one of a series of transverse shafts 32. Each arm 31 has a companion arm 33 mounted upon the rearmost shaft 32 of the previously mentioned series of transverse shafts and is connected thereto by link 34. The links 34 connected to the driven members 29, which are under the control of the amount keys, are provided with rack portions 35 which are arranged to engage with pinions 36, the pitch line of one of said pinions being only shown in Fig. 2 of the drawings. These pinions are supported in a frame 37 and have connected thereto pinions 38 which engage with pinions of the totalizer elements 180

39 through which gear connections the elements 39 are actuated an extent depending upon the amount keys depressed. As fully shown and described in the copending application previously mentioned, the totalizers, of which there are two, are normally out of engagement with the actuating racks 35 controlled by the amount keys and are arranged to be brought into engagement 5 with said racks by an operation of the "cash" key alone or by an operation of the "cash" key and the "foreign" key. As fully explained in the aforementioned application, all of the sales made by the clerks operating 10 under the cashier having charge of the machine are entered in one of the totalizers, and whenever a sale is made by a clerk foreign to the cashier, that is a clerk from some other department than which the cashier has supervision of, the cashier operates the "foreign" key in connection with the amount and "cash" key, which "foreign" key controls mechanism for shifting the totalizer frame 37 so as to bring the second 15 or foreign totalizer in position to engage with the actuating racks 35 controlled by the amount keys. This shifting and rocking of the frame carrying the totalizer is only briefly mentioned here and for a detailed description 20 of the mechanism for accomplishing this result reference may be had to the aforementioned application.

The differential movement of the members 29 is brought about in the following manner: By reference to Fig. 2 it will be seen that the pivotal points of the levers 26 upon the driven members 29 vary, from which it is obvious that if the upper portion of the levers 26 are successively prevented from 25 moving by the key pins 26^a while the lower portion of said levers are moved by the driving member 22, a differential movement will be imparted to the driven member 29 owing to the varying distances between the key pins 26^a and the connection of the levers 26 with the driven member 29. As the driving members 22 are all operated upon each 30 operation of the machine and it frequently occurs that in several banks there is no key depressed the levers 26 of said banks will rock idly about their pivotal points upon the driven members 29 without imparting any movement to said members.

Extending from each of the links 34 is a pin 40 which plays in a recess 41 formed in the upper end of an arm 42 projecting upwardly from one of the transverse shafts 32. Only several of these connections between shafts 32 and links 34 are shown in order to avoid confusion in the drawings, it being understood that there is one of such connections between each shaft 32 and its respective link 34 while the link under control of the foreign key is connected to a sleeve surrounding one of the shafts as fully

shown in the aforementioned application but not being shown here because of the fact that it forms no part of the present invention, it being thought that a mere mention of the manner of connection would suffice. 76

The sales slip is placed upon the table 384 (Fig. 1) and upon the operation of the crank handle 6 it is fed in the machine and receives three impressions from the type carriers, one of which impressions is upon 75 the original portion of the slip and the other two upon the duplicate portion, the said duplicate portion being severed between the impressions thereon and the severed part of the slip deposited in a suitable receptacle. The records made upon the sales slip comprise the cashier's symbol, the consecutive number of the sale, the date, and the amount of the transaction, the amount type carriers being set up by connections from 80 the shafts 32 under the control of the amount keys 2, while the cashier's symbol and the dating type carriers are adjusted by the cashier operating the machine, the consecutive number type carriers being advanced automatically one step upon each 85 operation of the machine. A further description of the adjustment of the various type carriers for recording upon the sales slip and the manner of feeding said sales slip and severing a portion thereof may be had by reference to the aforementioned application.

Two sets of type carriers 44 and 45, Fig. 2, are provided for recording upon a check strip 46. The type carriers 44 are arranged to print the cashier's symbol, the consecutive number, the date and the amount of the transaction, while the type carriers 45 are arranged to print the class of transaction, 100 whether it is "cash", "C. O. D." or "charge", the composite number representing the station, department and clerk and the character "F" if the sale is made by a foreign clerk. The amount type carriers as well as the 105 transaction type carriers and the type carriers representing the composite number and whether the sale is foreign or one made by the clerk operating under the cashier, are connected by links 47 (Fig. 2) to arms 48 extending downwardly from the shafts 32, from which it will be seen that as the shafts are rocked under the control of the manipulative devices as hereinbefore described, a corresponding movement will be imparted 110 to the type carriers 44 and 45. The cashier's symbol, the consecutive numbering type carriers and the dating devices are geared to similar devices for recording upon the check strip and are simultaneously set up with said devices as fully shown and described in the aforementioned copending application. After the type carriers are set up impressions are taken therefrom upon the check strip by platens 49 and 50, which platens 115

are suitably operated by one of the driving shafts of the machine as described in the aforementioned application.

Devices are set up under the control of 5 the transaction keys 1, amount keys 2, and clerks' department keys 3 and 4 for punching characters upon the check strip symbolical of the amount and kind of transaction entered in the machine as well as the 10 clerk making the transaction and the department in which it is made, these perforations controlling subsequent accounting operations as will hereinafter more fully appear. The shafts 32 controlled by the amount keys, 15 clerk number keys, department and transaction keys have arms 51 extending upwardly therefrom (Fig. 5), which arms at their upper ends are connected to rods 52 and which rods in turn are connected to 20 yoke frames 53 pivotally mounted upon transverse shafts 54 extending from the rear toward the front of the machine and suitably supported in the frame work 12. The yoke members 53 are connected by rods 55 25 (Figs. 5 and 6) to selecting plates 56 which are slidably mounted in a frame 57 (Figs. 2, 5 and 6), which frame is pivotally mounted as at 58 to the rear frame work 12 of the machine. Directly beneath the selecting 30 plates 56 are punches 59 which are movably mounted in a frame work 60 suitably supported by frame work 61. Mounted in the frame 60 carrying punches 59 is a movable plate 62 having a thin plate 63 secured to 35 the upper edge thereof, which thin plate enters recesses 64 cut in the sides of the punches 60. Projecting from each side of the frame 62 is a pin 65 which enters a recess 66 formed in an arm 67 extending forwardly from a rock shaft 68. Upon the operation of the machine the check strip 46 is fed beneath the punches 59 as hereinafter described, at which time the supporting arms of the frame 62 carrying the punches 40 45 are rocked permitting said punches to be lowered into engagement with the check strip. Simultaneously with the lowering of the punches the frame 57 carrying the selecting plates 56 will also be lowered, the 50 said selecting plates having in the meantime been adjusted under the control of their manipulative devices.

The lowering of the frames 57 and 62 is accomplished as follows: The gear 10 has 55 formed in the side thereof a cam groove 70 in which plays a roller 71 projecting from the forward end of an arm 72 suitably supported upon a stub shaft 73 projecting from the frame work of the machine. This arm 60 extends rearwardly and at its extreme rearward end is provided with a notch 74 in which plays a pin 75 projecting from the forward end of a centrally pivoted arm 76. A link 77 connects the extreme rearward end 65 of the arm 76 to the extension of one of the

arms 67 carrying the frame 62 and the forward member of the centrally pivoted arm 76 is connected by a link 78 to the frame 57. From this construction it will be seen that as the arm 72 is rocked in a clockwise direction the link 77 projecting from the arm 76 will be elevated and the link 78 lowered. The elevation of the link 77 will rock the arms 67 which will lower the frame 62 carrying the punches permitting said 75 punches to come in contact with the check strip, while the link 78 will lower the frame 57 carrying the selected plates 56 into contact with the proper punches. The continued movement of said frame 57 forces 80 the punches 59 with which the plates 56 co-operate through the check strip while the remaining punches will be held elevated by said strip. After the selected plates 56 have operated the proper punches the cam groove 85 70 will operate the arm 72 so as to restore the parts to normal position as shown in Fig. 2. As the frame 62 is elevated the plate 63 carried thereby will engage with the shoulders formed by the upper edges of the 90 notches in the plungers 59 and positively elevate said plunger. Below the frame 60 which carries the punches 59 is a receptacle 79 into which are deposited the punchings 95 from the strip 46. This receptacle 79 is slidably mounted on the frame 61 and may be withdrawn when desired to empty the said receptacle of the punchings.

The check strip 46 is arranged to be fed in one direction to a position to receive the 100 perforated characters and then fed intermittently in a reverse direction to receive the printed data from the different groups of the type carriers during one cycle of operation of the machine. In the reverse feed 105 of the strip to the type carriers the same amount is not fed as when the strip moves forward to the perforating devices as that during the succeeding cycle of operation when the strip is fed to the perforating devices that portion of it bearing the printed and perforated data from the previous operation, will be in position to be severed by the knives which are mounted in rear of the perforating devices as hereinafter described. 110

The frame 61 in which the frame 60 carrying the punches 59 is mounted is in turn slidably mounted upon rollers 80 (Fig. 3) 115 suitably supported by the frame work 12 of the machine. The purpose of having this frame 61 mounted in such manner is to permit the withdrawal of the frame to enable the ready insertion of a check roll 81 from which the check strip 46 is fed. For 120 a detailed description of the manner of mounting this slidable frame 61 reference may be had to the aforementioned application. The check strip as shown in Fig. 2 is led from the supply roll 81 over a guide 125 130

811 between the type carriers 44 and platen 50 to the feed rollers 82 and 83 from whence the strip is fed between the type carriers 45 and platen 49 and thence beneath the punches 59. A guide for guiding the end of the check strip so that it will pass under the punches has been omitted from the drawing for the sake of clearness. The rollers 82 and 83 during the first part of the operation of the machine feed the check strip rearwardly to bring a portion thereof beneath the punches 59 and after the strip has been perforated by the punches 59 it is then fed forwardly to the type carriers 45, which record upon one side of the perforated data, as shown in Fig. 24, and then the strip is slightly fed forwardly so as to have an impression taken thereon from the type carriers 44 on the opposite side of the perforated data from the impression which is taken from the type carriers 45. These impressions from the type carriers 44 and 45 are taken near the last part of one complete cycle of operation of the machine and the check strip remains in the position in which it receives the impression from the type carriers 44 until the succeeding operation of the machine. At the next operation of the machine the strip is fed rearwardly by the rollers 82 and 83 to such an extent that the portion thereof printed and perforated at the previous operation will be carried beyond the perforating plungers 59 so as to be severed by knives 84 and 85, as hereinafter more fully explained. The rollers 82 and 83 are provided with pinions 86 and 87 respectively which mesh with each other (Fig. 8). This latter pinion meshes with a pinion 88 suitably secured upon the side 40 of the frame 61 which pinion in turn meshes with a gear 89 secured to one end of a sleeve 890, Fig. 16, loosely mounted upon a shaft 90 suitably secured within the frame work of the machine. Secured to this shaft 90 is a disk 91 having notches 92 cut in the periphery thereof, (Fig. 8). Adjacent to this disk and loosely mounted upon the shaft 90 is an arm 93 at the outer end of which arm is pivotally mounted a spring pressed 45 pawl 94 which engages with the notches 92 of the disk 91. A link 95 connects the arm 93 with a lever 96, the latter being mounted pivotally as at 97 to the left hand side frame of the machine. The upper end of the lever 96 is provided with a roller 98 which plays in a cam slot 99 formed in a gear 100 which is given one complete rotation upon each operation of the machine by an intermediate gear 1000, Fig. 2, the pitch 50 line only being shown, which gear is driven from the previously described shaft 9. The shape of the cam groove 99 is such that during the first half rotation of the gear 100 the notched disk will be rotated in an anti-clockwise direction to the extent of approxi-

mately three notches or about three-tenths of a rotation. The feed pawl 94 will be held temporarily in this advanced position due to the shape of the cam groove 99 and while in this position a bell crank lever 101 70 pivotally mounted upon the left hand side frame of the machine will be rocked in an anti-clockwise direction by a pin 102 projecting from a gear 103 contacting with the horizontal arm of said bell crank 101. The 75 gear 103 meshes with gear 1000 and receives a complete rotation during each operation of the machine. This rocking of the bell crank 101 will cause the vertical member thereof to contact with a pin 104 projecting from the feed pawl 94 and withdraw said pawl from engagement with one of the notches 92 of the disk 91. Immediately after the disengagement of the pawl 94 from its notch 92 the arm 93 carrying said pawl 85 will start on its return movement and the pawl will ride upon the surface of the disk 91 until it is forced into the next notch 92 of said disk by its spring, the remainder of the return movement of said pawl being 90 then imparted to the disk 91. This disk clutch mechanism 910, Fig. 16, which is fully shown and described in the aforementioned application, is connected with the gear wheel 89, through sleeve 890. This reciprocal movement of the gear 89, will through the gears 86, 87 and 88 cause the rolls 82 and 83 to feed the check strip rearwardly and forwardly, the strip being fed one-third greater distance rearwardly at 100 which time it receives the perforated data thereon than it is fed forwardly to receive the printed data.

The severing mechanism for the check strip is operated upon each operation of the 105 machine, but a check which is printed and perforated is not severed until the succeeding operation of the machine. This is because of the fact that the check strip is fed to the perforating devices first and then fed 110 back from said devices to the recording means in which position it remains until at the beginning of the succeeding operation of the machine. Upon the second operation of the machine the check strip is fed to such 115 an extent that the portion previously perforated and printed will be fed into position to be severed by the knives 85 and 86 in which position of the strip a fresh portion thereof is brought beneath the perforating devices. The knife 86, which is a stationary knife (Figs. 2, 16 and 18), is secured to the frame 60 in which are mounted the 120 perforating plungers 59. This knife has a suitable opening 105 through which the 125 check strip passes. The movable knife 85 is mounted upon pins 106 which project forwardly from a plate 107 secured to rock shaft 108 mounted within the slidable frame 61 which carries the check strip feeding de- 130

vices and punching mechanism. The shaft 108 is provided with a collar 109 (Fig. 16) which has a flaring mouth 110 into which projects a pin 111 extending from a rock 5 shaft 112 suitably supported by the frame work 12 of the machine and a bracket 1222 secured to an intermediate frame 1223. This rock shaft 112 has secured thereto a bell crank 113 (Figs. 16 and 18) the vertical 10 arm of which is provided with a pin 114 that plays in a recess 115 formed in the upper end of an arm 116 secured to a rod 117 supported by the frame work of the machine. Intermediate its ends this arm 116 15 is provided with a roll 118 which plays in the cam groove 119 formed in a disk 120 secured to a shaft 121, which shaft has secured thereto the previously described gear 100 (Figs. 2 and 8). Springs 122 surround 20 the pins 106 and have their ends abutting against the knife 85 and the plate 107 by which springs the movable knife is held resiliently in contact with the stationary knife 86. The shape of the cam groove 119 formed 25 in the disk 120 is such that the arm 116 carrying the roller 118 will first be rocked in an anti-clockwise direction near the half rotation of the shaft 121 and then returned to its normal position as shown in Fig. 18. 30 This movement of the arm 116 will rock the bell crank 113 in a clockwise direction which will cause the movable knife 85 to be lowered to sever the previously perforated and printed check from the check strip, after 35 which the parts will be returned to their normal position by the cam disk 120 and the above described intermediate connections. Assisting the cam 120 in its work in lowering the knife 85 is a spring 125 (Figs. 2, 40 16 and 18), which spring at one end is connected to the horizontal member of the bell crank 113 and at its other end to the back frame work of the machine. When the frame 61 is moved laterally in order to get 45 at the check roll 81 or other devices carried by the said frame the collar 109 carried by the shaft 108 (Fig. 16) will be withdrawn from engagement with the pin 111 on the shaft 112 and when thus withdrawn the 50 frame 107 carrying the pins 106 which support the movable knife 85, which frame is secured to the shaft 108, will be rocked in an anti-clockwise direction (Fig. 18) through gravity, the rocking movement of said frame 55 being limited by a pin 1255 projecting from one of the side frames 61 with which pin a projection 126 of the plate 107 contacts. When the frame is restored to its normal position the flaring mouth 110 of the collar 109 60 will engage with the pin 111 of the shaft 112 and cause the shaft 108 and the frame 107 carried thereby with the movable knife 85 to be returned to its normal position.

The checks after being severed drop into 65 a hopper from which they are distributed

to a plurality of receptacles, each receptacle having a series of compartments, the selection of the receptacles and compartments being under control of the clerks' manipulative devices 3. By this arrangement 70 checks bearing data pertaining to the sales of each clerk are automatically assorted into their proper compartments from which they may be removed for the purpose of tabulating the totals of the sales made by 75 the various clerks or for any other purpose. This hopper as best shown in Figs. 2, 3 and 4 is composed of sectional parts 127, 128 and 129, the part 127 having a guiding flange 1277, Fig. 17, at its upper end to insure the depositing of the severed check in the part 127 of the hopper. Extending downwardly from a horizontal cross bar 130 (Figs. 3 and 23) is an arresting plate 131 which arrests the descent of the severed 80 check 46.

A differentially movable arm 132, (Figs. 3, 13, 14, 15, 21 and 22,) is secured to a vertical shaft 133 which shaft is suitably mounted in horizontal cross bars which 85 form a part of the frame work of the machine. This differentially movable check delivering arm is provided with a clamping jaw 1330 which is pivoted to said arm as at 134. This clamping jaw 1330 is arranged 90 to coöperate with a companion jaw 135 which is mounted stationarily upon the differentially movable member 132, the jaw 1330 being held normally in position to clamp a check between it and the jaw 135 100 by a spring 136, the ends of which spring are secured to a stud 137 projecting from the movable clamping jaw 1330 and from a stud 138 extending upwardly from a member 139 which is pivoted to the differentially 105 movable arm 132 as at 140. When in normal position as shown in Figs. 13, 14 and 21 the gripping members 1330 and 135 of the differentially movable arm are held in 110 closed position with a check gripped therebetween and when said arm is adjusted to deliver the check to any one of a plurality of check receptacles 141 the clamping arm 1330 is released by the pivot member 139 rocking about its pivot 140 so as to carry 115 the spring 136 across the center of the pivot of said pawl so as to relieve the tension of the spring 136. When the tension of said spring is thus released a spring 142 comes into play to release the check by forcing the 120 clamping member 1330 from engagement with its companion member 135 and thereby depositing the check in the selected receptacle 141. Immediately after the beginning of movement of the check delivering 125 arm 132 to deliver a check to one of the receptacles a door 332 (Figs. 14 and 23) pivotally mounted upon a rod 333 supported by the horizontal cross frame 130 will be 130 swung by a spring (not shown) to close the

side of the lower portion 129 of the check hopper and thereby prevent the accidental displacement of the check which is deposited there while the delivering arm is carrying a previously severed check to its proper receptacle. Upon the return of the delivering arm 132 to its normal position the inner edge of the jaw 135 carried by said arm will engage a projection 331 extending from the door 332 and cam said door into a position where the deposited check may be withdrawn by the delivering arm from the lower portion 129 of the check hopper without interference from said door. At its extreme free end, the check delivering arm 132 carries an anti-friction roller 350, (Figs. 14, 21 and 22), which during the last increment of movement of said arm on its return movement passes into engagement with a guide plate 351 suitably mounted upon the horizontal cross frame 130. The purpose of this roller 350 and guide plate 351 therefor is to insure the coacting of the jaw 135 with the projection 331, Figs. 21 and 23, of the door 332 to open the latter and also to insure the coacting of the extension 330 of the lower portion 129 of the check hopper with the spring operated pawl 328 to release the clamping jaw 1330 and permit the latter to clamp the check 46 supported by the plate 131.

The check receptacles, as will be seen by reference to Figs. 3, 4, 13 and 14, are arranged concentrically about the shaft 133 supporting the check delivering arm 132, the said receptacles being suitably secured to arms 143 of a circular plate 144 which is secured near the upper end of a vertical shaft 145 which extends into a sleeve 146 suitably supported by the main portion of the frame work 12, the lower end of this shaft 145 being supported by bearing 147 extending upwardly from the base of the machine. The receptacles 141 at their lower ends are supported upon a plate 148 which in turn is secured to the shaft 145. There are ten of these receptacles 141 the selection of any one of the last nine of the receptacles being controlled by the tens bank 3 of clerks' keys, while the first is selected when one of these keys is not depressed, and each one of these receptacles 141 is divided into a series of ten compartments, the selection of any one of the top nine of which is controlled by the units bank of clerks' keys 3, while the bottom one is selected when no key in this latter bank is depressed, as will more fully hereinafter appear. In normal position the check delivering arm 132 is directly under the lower portion 129 of the check hopper in which position it is out of co-operative relation with any one of the receptacles 141 as can be plainly seen by reference to Figs. 13 and 14.

As previously stated, the check is perfo-

rated and printed with suitable data upon the first operation of the machine and upon the second cycle of operation the previously printed check is severed and it is not until the third operation of the machine 70 that the printed check is delivered to the proper compartment and receptacle, although during the same operations in which the printed and perforated data is entered upon the check there is set mechanism for 75 determining the receptacle and compartment in which the check is to be delivered. There is imparted to the check delivering arm a movement at each operation of the machine regardless of whether a key in the 80 tens bank of the clerks' keys is depressed or not. If no key of the tens bank of clerks' keys is depressed the check delivering arm will have imparted thereto one degree of movement so that the check may be 85 delivered to one of the compartments of the first receptacle which compartments are controlled by the units bank of clerks' keys. If the one key of the tens bank is depressed the check delivering arm will have two degrees of movement to bring it into position to deliver the check into the second receptacle. If a five key of the tens bank of clerks' keys 3 is depressed the arm will have six degrees of movement and so on up to the 90 nine key in which case the arm will deliver the check to the tenth check receptacle counting in a clockwise direction from the check delivering arm 132 in Figs. 13 and 14. One of the principal reasons for moving the check delivering arm upon each operation of the machine is for the purpose of operating the check gripping member 133 so that as said delivering arm 132 is restored to its normal position it can grip 95 the check which has been deposited upon the arresting plate 131 while said delivering arm is away from normal position. The release of this check gripping member will hereinafter be more fully described.

Each of the ten check receptacles 141 is divided into a series of ten compartments 149, several of which are shown in Fig. 4 of the drawings. Directly back of the compartments 149 (except the bottom one) of 100 each receptacle 141 is a series of movable deflecting plates 150 which are normally drawn into vertical position as shown in Fig. 4 by light coil spring 151 connected to arms 152 projecting rearwardly from the 105 deflecting plates and projections 153 extending from the rear wall of the receptacle 141. The deflecting plate (not shown) for the lowest compartment of each receptacle is stationary, and always in deflecting 110 position, so that the check will be delivered therein if no key in the units bank of clerks' keys is depressed. To these arms 152 are connected the lower ends of rods 154, 115 the upper ends of which are provided with 120

enlarged heads 155, which enlarged heads are arranged to be engaged by a selecting finger 159 carried by the check delivering arm 132. This selecting finger is differentially adjusted under the control of the units bank of clerks' keys 11 as will appear more fully hereinafter.

It was previously stated that the check which was perforated and printed upon one cycle of operation was not delivered until the second cycle of operation thereafter, although the compartment of the receptacle in which the check was to be delivered was determined upon the same cycle of operation in which the check was printed and perforated. This mechanism for selecting the receptacle and compartment in which the check is to be delivered at some subsequent operation from that in which it is issued will now be described.

Extending rearwardly from the shaft 32, which is controlled by the tens bank of clerks' keys 3, is an arm 157 which at its rearward end is connected to the upper end of a rod 158 (Fig. 2), the lower end of said rod being connected to an arm 159 (Fig. 4) which is secured to a shaft 160 supported by brackets 161 suitably mounted in uprights of the machine. This shaft at its other end, Fig. 14, has secured thereto an upwardly extending arm 162 which at its upper end is connected by a link 163 (Fig. 3) to a slide 164, which in turn is mounted upon a rod 165 supported by brackets 166, the latter being supported by the horizontal cross frame 130. This shaft 160 is divided into two sections one half of which is driven by connections under the control of the tens bank of clerks' keys while the other half is driven by connections under the control of the units bank of clerks' keys. The slide 164 is provided with a recess 167 in which plays an extension 168 of a sliding selecting bar 169 provided with a plurality of recesses 170. This sliding bar 169 is supported by a rotating frame 171 which in turn is supported by brackets 172 suitably mounted upon the horizontal cross frame 130 (Figs. 3 and 10). From this description it will be obvious that the movement imparted to the rock shaft 32 under the control of the tens bank of clerks' keys 3 will, through the intervening connections just described, impart a similar degree of movement to the sliding bar or member 169. This adjustment of the sliding bar 169 occurs approximately during the first half of a cycle of operation of the machine, after which adjustment the frame 171 is rotated in a clockwise direction (Fig. 10) by suitable mechanism hereinafter described. By this rotation the offset 168 of the sliding member 169 will be carried out of the recess 167 of the sliding plate 164, the said sliding member 169 being locked from ac-

idental or intentional displacement by a flange 1730 which flange is in the shape of an annular ring formed internally of a housing 174 (Fig. 12), which housing is secured to the horizontal cross frame 130. 70 As the member 171 is rotated the flange 1730 will pass into one of the recesses 170 of the slideable member 169 and thereby prevent any displacement of said member.

The rotating member 171 is secured to 75 shaft 173, which shaft at its right hand end (Fig. 3) is recessed so as to receive an extension 174 of a shaft 175, which shaft is supported at its right hand end by the bracket 172. This manner of connecting 80 the shafts 173 and 175 is done purely from a manufacturing standpoint in order that the parts upon each shaft may be assembled independently and connected by the extension 174 passing into the recess of a shaft 85 173. Secured to the shaft 175 is a ratchet wheel 176 which is provided with four ratchet teeth, with which the pawl 177 is arranged to engage. This pawl 177 is carried by an arm 178, which arm is loosely 90 mounted upon the shaft 175. A rod 179 (Figs. 10 and 19) extends downwardly from the arm 178 and at its lower end is connected to an arm 180 which arm is pivoted upon a stub shaft 181 extending from a 95 bracket 182 secured to one of the uprights 183 which support the cross frame 130. The arm 180 is provided with a roller 184 which extends into the cam groove 185 formed in a disk 186 secured to a shaft 187, which shaft 100 is given a complete rotation at each operation of the machine. The shape of the cam groove 185 is such that during the adjustment of the differentially movable selecting member 169 the arm 178 carrying the pawl 105 177 will be moved in an anti-clockwise direction (Fig. 10), causing the pawl 177 to pass idly around the ratchet wheel 176 to the extent of about a quarter of a turn. After the differentially movable selecting member 110 169 has been positioned the cam groove will elevate the arm 178 carrying the pawl 177 thereby causing the ratchet 176 and shaft 175 to which it is secured, to be rotated a quarter turn, which rotation will be imparted to the shaft 173 carrying the rotatable member 171. The rotary shaft 187, supported by hangers 1870 extending downwardly from the frame 130, has secured thereto a bevel gear 188 (Fig. 9), which gear 115 meshes with a similar gear 189 secured to the lower end of a vertical shaft 190, which shaft at its extreme upper end is provided with a bevel gear 191 (Figs. 2 and 16) which meshes with a similar gear 192 secured to a 120 stub shaft 193. This latter shaft (Figs. 8 and 16) is provided with a gear 194 which meshes with a previously described gear 100 carried by the shaft 121. For the purpose of assembling, the vertical shaft 190 is split 125 130

into several sections and connected by suitable collar and pin connections 194 and 195 respectively, as shown in Figs. 2, 3, 4 and 16. Brackets 1900 extending from the frame work suitably support the several sections of the shaft 190.

It has been described how the differentially adjustable slide 169 has been positioned in the frame 171 under the control 10 of the tens bank of clerks' manipulative devices 3; also how the said frame 171 has been given a quarter rotation upon the same cycle of operation in which the check strip has the desired data recorded and perforated thereon. It will now be described how 15 this previously adjusted member 169 will control the selection of one of a plurality of coupling rods arranged to couple a driving member having a constant extent of movement with the differentially adjustable check delivering arm 132.

The driving member 196 (Fig. 14) is pivoted as at 197 to a frame 198 which in turn is suitably secured to the horizontal cross member 130. The driving member 196 is of a bell crank formation and the horizontal arm thereof is connected by a link 199 to a lever 200 (Fig. 15), which lever is pivoted as at 201 to a bracket 202 secured to the 20 under side of the horizontal cross frame 130. At its lower end the lever 200 is provided with a roller 203 which plays in a cam groove 204 formed in a disk 205 secured to the previously described shaft 187. The shape of this cam groove 204 is such that immediately after the beginning of the rotation of the shaft 187 the driving member 196 (Fig. 14) will be given a movement in an anti-clockwise direction through the intermediate 25 connections previously described, and near the end of the rotation of said shaft restore said driving member 196 back to its normal position. This driving member 196 is normally locked by pawl 206 (Fig. 14), 30 which pawl is pivoted upon the frame 198 which also supports the driving member. This pawl 206 is connected by a rod 207 to a lever 209 (Fig. 19), which lever is pivoted upon the stub shaft 2010 supported by 35 bracket 202 secured to the cross frame 130. At its lower end this lever is provided with a roller 211 which plays in a cam groove 212 formed in a disk 213 secured to the shaft 187. Immediately upon the beginning of 40 the rotation of the shaft 187 the lever 209 will be rocked in a clockwise direction (Fig. 19) and through the rod 207 (Figs. 14 and 19) withdraw the free end of the pawl 206 out of engagement with the driving member 196 leaving the previously described 45 cam 205 and intermediate connection to rock said driving member.

It will be seen from the above that the driving member 196 is given its movement upon every operation of the machine, but

as previously stated, during the first operation of the machine at the beginning of the day's business the sales check is perforated and recorded during which operation the selection of the compartment of the receptacle in which the check is to be delivered is determined, but as the check is not severed until the second operation it is not necessary to actuate the selecting mechanism before the severing of the check, and 70 as shown herein the actuation of the selecting mechanism does not take place until the second cycle of operation of the machine subsequent to the operation in which the data is recorded and perforated on the 75 check. It was previously described how the selecting bar 169 is differentially adjusted and rotated in the carrier 171 during the cycle of operation in which the data was recorded and perforated upon the check. 80 Upon the second cycle of operation of the machine in which the check is severed, as previously described, the carrier 171 is given another quarter of a rotation by the pawl 177 engaging with the ratchet wheel 90 176, the completion of which movement occurs subsequently to the restoration of the driving member 196. During the completion of the movement of the carrier 171 the offset 168 of the previously adjusted selecting 95 member 169 (Figs. 3, 10, 14 and 15) will engage with one of a plurality of coupling rods 215 and elevate said rod so that an eyelet 216 formed near the outer end of said rod will encircle one of the series of studs 217 projecting 100 downwardly from the driving member 196. The other ends of the rods 215 are pivotally mounted to arms 218 pivotally mounted upon a rod 219 supported upon a frame 220, 105 which in turn is secured to rods 221 which are slidably mounted in a frame 198 secured to the previously mentioned horizontal cross frame 130. The frame 220 carries a rack plate 223 which meshes with a pinion 224 secured to the previously described vertical shaft 133 which carries the 110 check delivering arm 132.

By reference to Fig. 14 it will be seen that the recesses 216 formed in the outer ends of the coupling rods 215 are located varying 115 distances from the pivotal point 197 of the driving member 196 with the result that the frame 220 carrying the coupling rods 215 has imparted thereto a differential movement by the driving member 196 which has a constant movement. It is obvious that if the coupling rod 215 nearest the fulcrum point 197 of the driving member is connected to the latter member the frame carrying said coupling rod will not be given as great a throw as if one of the other rods were coupled to said driving member and by this construction the frame 220 receives its differential movement and through the 120 rack plate 223 carried by said frame and 125 130

pinion 224 will rotate the shaft 133 carrying the check delivering arm 132 varying distances depending upon the coupling rod 215 connected to the driving member 196.

5 It is understood of course, that if no key in the tens bank of clerks' keys is depressed that the slide 169 will not be slid out of its normal or zero position and that with the slide in this position the coupling rod 215 10 nearest the fulcrum point 197 of the driving member will be coupled to the latter so that the arm 132 will be moved above the first receptacle, counting from the normal position of the arm 132, to deposit the check 15 therein. If the "one" key in the tens bank is depressed the second rod 215 from the fulcrum point 197 will be coupled with the member 196 so that the check will be delivered into the second receptacle and so 20 on, the last coupling rod being connected to the member when the "nine" key in this bank is depressed the check being then delivered in the last or tenth receptacle counting from the normal position of the arm 132.

25 The eyelets 216 extend downwardly from the coupling rods 215 and each is provided with two flanges 225. The plate 222 is provided with inverted L-shaped guide flanges 226 (Figs. 14 and 15) through which the 30 eyelets 216 pass when the driving member 196 is operated. By reference to Fig. 14 it will be seen that that portion of the guide flanges 226 through which the eyelets pass are struck from an arc of the circle 35 scribed from the pivotal point 197 of the driving member 196.

When one of the coupling rods 215 has been lifted by the selecting slide 169, as previously described, the lower flange 225 of the 40 eyelet 216 of the selected rod 215 will pass above the uppermost portion of the guide flanges 226 so that when the driving member 196 is reciprocated as previously described the selected coupling rod will positively be held in engagement with the pin 217 of the driving member because of the fact that the lower flange 225 will ride upon the upper surface of the guide flanges 226. One of the rods 221 carrying the frame 220 45 has a notch 227, Figs. 14 and 15, formed near one end thereof and in this notch projects the free end of a pawl 228 pivotally mounted upon the under side of the plate 222 by which pawl the frames 220 and the 50 coupling rods 215 are prevented from accidental displacement. This pawl is connected by a rod 229 to the previously described lever 209 (Fig. 19) which lever, as already described, is rocked in a clockwise direction 55 upon the very beginning of the rotation of the shaft 187, by which movement the pawl 228 is rocked out of the recess 227 so that the frame 220 carrying the coupling rods may be adjusted. When the frame 60 65 220 is driven by the member 196 upon

the coupling of one of the said rods to the driving member, the reduced portion between the flanges 225 of the eyelets carried by the uncoupled rods will pass through the recesses formed by the guiding flanges 215 70 with the upper set of flanges 225 of the eyelets 216 above the guiding flanges 226 and the lower set of flanges 225 below the guiding flanges and thereby prevent accidental coupling of the uncoupled rods with the 75 driving member 196 during the movement of said member.

Immediately after the restoration of the driving member to its normal position and prior to the completion of a quarter turn of 80 the carrier 171 to couple one of the rods to the driving member a restoring frame 230 (Figs. 10, 14 and 15) will be rocked to uncouple the previously coupled rod 215 from the driving member 196. Ordinarily the 85 coupled rod 215 will drop by gravity from engagement with the driving member when said member reaches its normal position, but in case it does not the restoring frame 230 is operated positively to disconnect the driving rod therefrom, immediately after which the frame 171 carrying the selecting slide 169 completes its quarter rotation and through said slide couples one of the rods to the driving member so that upon the beginning 90 of the next operation of the machine the check delivering arm will be operated to deliver the check into the proper receptacle.

The restoring frame 230 is of yoke formation and is secured to a shaft 231 supported by brackets 232 upon the frame 198. Near one end this shaft 231 has an arm 234 (Fig. 14) secured thereto, which arm has fastened to its free end the upper end of a pitman 235 (Figs. 10 and 15), the lower end of 100 which is bifurcated so as to straddle a collar secured to the shaft 187. Near its lower end this pitman 235 is provided with a roller 236 which plays in a cam groove 237 formed in a disk 238 secured to the shaft 187. The 105 shape of this cam groove is such that near the end of rotation of the shaft the pitman 235 will be elevated (Fig. 10) and rock the shaft 231, which will cause a rocking of the restoring frame 230 in a clockwise direction to 110 disconnect the coupling rod from the driving member 196. Immediately after this the restoring frame will be returned to its 115 normal position to permit the coupling of the same rod or a different rod by the flange 120 168 of the previously adjusted selecting slide 169.

The frame 171 carrying the selecting slide 169 is provided with four such slides and the slide that is set up under the control of the tens bank of clerks' keys 3 is carried by the frame 125 171 to a position pointing downwardly (Fig. 10) during the same operation in which it is adjusted, during which operation also occurs the recording and perforating of the 130

check strip. Upon the succeeding operation when the check strip is severed the carrier 171 is rotated another quarter of a turn carrying the previously adjusted slide 169 to 5 a position to select one of the coupling rods 215 so as to connect it with the driving member 196, but this selection of the coupling rod does not occur until the very end of the 10 second cycle of operation, at which time the driving member has been returned to its normal position from an operation, it being understood that the driving member 196 receives a constant movement at each operation of the machine. This coupling of one 15 of the rods to the driving member by the selecting slide determines the extent of movement to be imparted to the check delivering arm 132 upon the third cycle of operation by which time the severed check will 20 have been delivered to the previously described gripping plate 1330 and 1335 of the delivering arm 132. During the third cycle of operation of the machine in which cycle the check will be delivered to its proper receptacle, the carrier 171 will be given another quarter of a turn so as to carry the selecting slide 169 to a position pointing upwardly from the shaft upon which the carrier is rotated. During the time the selected 25 slide 169 has traveled from the position in which it is differentially adjusted to the position in which it points upwardly from the shaft about which the carrier rotates, the adjusted slide is locked by the flange 1730 30 entering one of the recesses 170 of the slide 169, but when it reaches the position in which it points upwardly from the shaft 173 about which it rotates, the slide is free to be restored to its normal position due to a 35 cut out portion 240 of the flange 1730. Upon 40 the beginning of the fourth cycle of operation of the machine an arm 241, (Figs. 3, 10 and 14,) slidably mounted upon a rod 242 supported by the brackets 166 will engage 45 with the end of a slide 169 and restore said slide to its normal position after which the frame carrying said slide will be given a quarter rotation making a complete rotation for said frame thereby bringing said slide 50 back to its normal position. This restoring arm 241 is connected to one end of a link 243 (Figs. 14 and 20) which link at its other end is connected to the upper end of an arm 244 pivotally mounted upon the stud 160 55 (Figs. 3, 4 and 20). Near its pivotal point the arm 244 is provided with a roller 245 which plays in a cam groove 246 secured to the disk 247 fast to the shaft 187. The shape of the groove 246 is such that upon the beginning 60 of each operation of the machine the arm 244 is rocked in a clockwise direction and through the link 243 operates the restoring arm 241 to restore the selecting slide 169 to its normal position, it being under-

stood that for every operation of the restoring arm 241 there will be a slide in position 65 to be acted thereupon by said arm.

It has been stated that the carrier 171 is given a quarter rotation upon each operation of the machine but this rotation is not 70 given until near the end of a cycle of operation and in order to prevent accidental rotation of said carrier the shaft 175 which drives the carrier has secured thereto a disk 248 with four notches 249 cut therein at 75 equal distances about the periphery of said disk (Figs. 3, 10 and 20). Normally a rod 250 extends in the lowermost one of these notches 249 and prevents the rotation of said disk. When the pawl 177 engages with one 80 of the teeth of the previously described ratchet wheel 176 fast to the shaft 175 the rod 250 is withdrawn so as to permit said pawl to rotate the shaft and the carrier 171. This rod 250 is supported by arms 251 the 85 lower one of which is pivoted upon the stub shaft 181 while the upper arm is pivoted upon a stud 2510 projecting from a bracket 2511 secured to the cross frame 130. The lower one of the arms 251 is provided with a 90 roller 252 at its free end which plays in a cam groove 253 secured to a disk 254 fast to the shaft 187. The shape of the groove 253 is such that immediately before the pawl 177 starts to rotate the shaft 175 95 and the carrier 171 driven thereby the rod 250 will be withdrawn from the notch 249 to permit the rotation of the carrier through the pawl 177. Immediately after the quarter turn has been imparted to the 100 carrier by the pawl 177 heretofore described, the cam groove 253 cams the arm 248 and securely locks the carrier from accidental rotation.

The above described mechanism relates 105 to the selection of the check receptacle in which the check is to be delivered. Each of these receptacles, as already stated, is divided into a plurality of compartments into which the delivered checks are deflected by 110 a series of plates which are actuated by a finger carried by the check delivering arm as previously described. This finger is differentially adjusted under the control of the units bank of clerks' keys 3 and the 115 mechanism for adjusting this finger will next be described. The units bank of clerks' keys controls the adjustment of a selecting slide in identically the same manner in which the slide 169 is controlled by the tens bank 120 of clerks' keys 3. This slide controlled by the units key is mounted in a rotatable carrier which is given a quarter turn upon each cycle of operation in exactly the same manner as the previously described carrier 171 125 and the parts for adjusting the units slide mounted in the carrier will be identified by the same reference numeral as used in de-

scribing the parts for adjusting the slide under the control of the tens bank of clerks' keys.

The previously described finger 156 for actuating the deflecting plates of the check compartments is splined upon a shaft 260 Figs. 3, 10, 15, 21 and 22, which shaft is supported by brackets 261 extending from the underside of the check delivering arm 132. The finger 156 being splined upon the shaft permits lateral movement of said finger independently of the shaft but causes the said finger to be rocked with the shaft. A slide 262 is supported by brackets 263 on the under side of the check delivering arm 132 and one end of said slide embraces the finger 156 so as to cause the adjustment of said finger. This slide near its center has extending downwardly therefrom a flange 264 (Figs. 3 and 22), which flange is provided with a pin 265 that projects in the forked portion formed in the upper end of a vertical member of a bell crank lever 266, which is pivoted as at 267 to a bracket 268 extending downwardly from the check delivering arm 232. The horizontal member of the bell crank 266 is forked as at 269, which forked portion is provided with rollers 270 that project in an annular groove 271 formed in a collar 272 loosely mounted upon the shaft 133 to which the check delivering arm 132 is secured. The lower end of this collar 272 is provided with another annular groove 273 in which extends rollers 274 projecting from the forked portion of one end of a centrally pivoted lever 275, which lever is pivoted as at 276 to a hanger 2760 supported by the cross frame 130. The other end of the lever 275 is connected by a link 277 to an arm 278 supported upon a stub shaft 279 extending from a portion of the hanger 2760. The hub of the arm 278 has secured thereto an arm 280 which is connected by link 281 to an arm 282 (Figs. 9 and 13), which arm extends from a sleeve 283 mounted upon a shaft 284 supported by arms 285 which extend from the housing 174 secured to the horizontal cross frame 130. The sleeve 283 has a series of spirally arranged fingers 286 projecting therefrom, which fingers are arranged to be acted upon by the projection 168 of the slide 169 positioned under the control of the units bank of clerks' keys 3. By this spiral arrangement of the fingers 286 the arm 282 is differentially rotated about the shaft 284 and through link 281, arms 278, link 277 and lever 275 differentially adjusts the collar 272 (Fig. 3) upon the shaft 133. This differential adjustment of the collar 272 will through the bell crank 266 adjust the slide 262 mounted upon the check delivering arm 132, which slide will differentially adjust the finger 156 (Fig. 21) to bring the said

finger into coöperative relation with the head 155 of one of the rods 154 for actuating the deflecting plates 150 (Figs. 3 and 4).

There are ten fingers 286, one for each of the ten positions of the slide 169, including the normal position of the latter. When no key is depressed in the units bank of clerks' keys the slide 169 remains in normal position and when the finger 286 corresponding to the normal position of the slide is in engagement with the projection 168 on the slide the finger 156 is not in coöperative relation with any of the heads 155 of the nine rods 154. There are nine of these rods 154 for each receptacle, there being one rod for each deflecting plate which as above stated, is stationary, and when one of the fingers 286 appropriate to one of the rods 154 is in engagement with projection 168 the finger 156 is then in coöperative relation with the head 155 of that particular rod.

Each of the heads 155 on the rods 154 is provided with an offset 287 (Fig. 11) which when any of the rods 154 is actuated by the finger 156 will be engaged by cross bar 288 of a yoke shaped frame 289 which is pivotally mounted as at 290 to brackets 291 secured to the check receptacles 141. These yoke frames, of which there is one for each check receptacle, are held in engagement with the offsets 287 by coil spring 292 that surrounds the pivotal point 290 of each frame 289. When a second rod 154 of any one of the check receptacles is actuated the offset 287 will rock the frame 289 so as to release the previously actuated rod and permit the said rod and its deflecting plate to be restored to its normal position by the spring 151 (Fig. 4).

It is to be understood that while the spirally arranged fingers 286 are actuated upon the second cycle of operation of the machine that it is upon the third cycle of operation that the check delivering arm is actuated bringing the previously adjusted finger into coöperative relation with its rod 154 so as to select the proper compartment in which to deposit the checks. Having adjusted the finger 156 to select the compartment in which the check is to be delivered, the shaft 260 carrying the finger 156 is rocked after the check delivering arm 132 has been moved to the proper receptacle. This rocking of the shaft 260 carrying the finger 156 is accomplished as follows: This shaft near one end has secured thereto an arm 292 (Figs. 3 and 21) which arm is connected by link 293 to a collar 294 loosely mounted upon the shaft 133. This collar is provided with an annular groove 295 in which projects rollers 296 extending from the forked portion of a lever 297, which lever is pivoted upon the hanger 2760. The other end of the

lever 297 is connected by a link 298 to the horizontal member of a bell crank 299 which is pivoted also upon the hanger 2760, (Figs. 3 and 15). The vertical member of the bell crank 299 is provided at its lower end with a roller 300 which plays in the cam groove 301 of a disk 302 secured to the shaft 187. The shape of this groove is such that after the adjustment of the check delivering arm 10 it will rock the bell crank 299 in a clockwise direction (Figs. 3 and 15). This rocking of the bell crank will through the link 298 rock the lever 297 in an anti-clockwise direction, which lever, through pins 296, will lower 15 the collar 294 upon the shaft 133. This lowering of the collar 294 will, through the link 293 and arm 291, rock the shaft 260 thereby causing the finger 156 to act upon the head 155 of one of the rods 154 which 20 causes its deflecting plate 150 to be inclined in order to direct the deposited check to the proper compartment 149. After the actuation of the rod 154 and its deflecting plate 150 the shaft 260 will be restored to its normal position by the cam 302 and intermediate connections. It is understood, of course, 25 that if no clerks' key in the units bank is depressed the finger 156 will not be in coöperative relation with any of the heads 30 155 of the rods 154 as above stated, and therefore none of the movable deflecting plates 150 will be raised to deflecting position upon the upward rocking movement of the finger 156, this movement at this time 35 being idle. As the deflecting plate for the lowest compartment is stationary, however, the check will be delivered in this compartment as none of the movable deflecting plates have been moved into deflecting position.

40 The shaft 260 near the clamping jaws 1330 and 135, Figs. 21 and 22, has secured thereto an arm 325 which is connected to an arm 326 by a rod 327. The arm 326 has projecting from the free end thereof a pin 340 that extends into an opening formed in the pivotal member 139. When the shaft 260 is rocked as above described the arm 326 will be rocked in a clockwise direction, Fig. 21, by which movement the pin 340 carried 45 by said arm will cause the member 139 to rotate in a clockwise direction. As the spring 136 passes over the pivotal point 140 of the member 139 the tension of said spring will be relaxed permitting the spring 142 to 50 rock the gripping arm 1330 out of engagement with the stationary arm 135 thereby depositing the check in the selected receptacle, which check will be directed by the operated deflecting plate 150 to its proper 55 compartment 149. When the gripping arm 1330 is thus rocked by the spring 142 the spring operated pawl 328 will pass out of a notch 329 into engagement with the inner edge of the gripping jaw 1330 and thus 60 hold the jaw 1330 out of engagement with

stationary jaw 135 until the very last increment of movement of the check delivering arm 132 on its return movement to normal position. As the check delivering arm 132 nears its normal position the extension 330, 70 Figs. 21 and 23, of the lower portion of the check chute 129 will contact with the pawl 328 and rock said pawl against the tension of its spring until the free end thereof is presented to the notch 329 of the jaw 1330, 75 at which time the spring 136 will draw the jaw 1330 into engagement with the jaw 135 with a check clamped therebetween. Prior to the tripping of the pawl 328 the member 139 will be returned to the position shown 80 in Fig. 21 through connections with the shaft 260, in which position the spring 136 will be under tension so that when said pawl 328 is tripped the jaw 1330 will be drawn into contact with jaw 135. 85

After the shaft 260 is returned to its normal position the carrier 171 having mounted therein the units selecting slides 169 will be rotated and if the selecting slide which is brought into coöperative relation with one of the fingers 286 has previously been adjusted under control of a key of higher value than previously operated in the units bank of keys the offset 168 of said slide will contact with one of the fingers 286 and rock the sleeve carrying said fingers a greater extent than which it was rocked at the previous operation, which, through the intermediate connections, causes a greater lateral movement of the finger 156. If the selecting slide 169 were adjusted under control of a key of lower value in the units bank of keys than the one previously operated, a spring 303, Fig. 13, surrounding the sleeve 283 will rock said sleeve carrying the fingers 286 in a 100 counter-clockwise direction until one of the fingers 286 contacts with the offset 168 of one of the slides 169 carried by the rotatable carrier 171, which, through the connections from the sleeve 283 to the finger 156, will 105 cause the latter to be returned toward zero position. 110

The slides 169, of which there are four, mounted in the units carrier 171 are restored to their normal zero position in precisely the 115 same manner in which the previously described selecting slides 169 controlled by the tens bank of clerks' keys are restored.

Operation: Having described in detail the various parts of the machine a résumé of the 120 operation of the various parts will be here given in order that the mind may be refreshed as to the various functions performed by the machine.

The cashier on receiving an itemized sales 125 slip from one of the clerks under her supervision, inserts the sales slip upon the table shown in Fig. 1 and then depresses the keys corresponding to the class of transaction, the amount of transaction and the keys rep- 130

- resenting the clerk making the sale, the department in which it is made, and the station at which the machine is located. Having pressed the proper keys she then turns the operating handle 6 and, through the links 26 and driving members 22, imparts a differential movement to the driving members 29, which movement will be transmitted to the shafts 32 by the arms 42 extending upwardly therefrom and in engagement with the links 34 which are connected to the driven members 29 and supported by the arms 31. The links 34 which coöperate with the amount banks of keys will, through their rack portions 35, actuate the totalizer 39 an extent corresponding to the amount keys depressed. The rocking movement imparted to the shafts 32 will be transmitted through suitable connections to type carriers for printing the amount in triplicate upon a sales slip, as fully shown and described in the aforementioned application. This movement of the rock shafts will also, through arms 48 extending downwardly therefrom and links 47, adjust type carriers 44 and 45 so as to print the kind of transaction, the amount thereof and a composite number representing the clerk making the sale, the department in which it is made, and the station where the machine is located, as shown in Fig. 24. In addition to this printed matter there will also be printed upon said check from type carriers suitably adjusted a symbol designating the cashier, the consecutive number of the sale and the date on which it is made. The rocking of the shafts 32 will, through arms 51, rods 52, yoke frames 53 and rods 55, Figs. 5 and 6, adjust plates 56 for actuating punches 59 whereby there will be perforated upon the check strip 46 characters symbolical of the amount of the transaction, the clerk making it, the department in which it is made and the kind of transaction. This setting of the type carriers for recording upon the sales slip and upon the check strip occurs during the same cycle of operation of the machine in which the keys representing the transaction are depressed and also during the same cycle of operation the punches 59 are operated to perforate suitable data upon the check strip 46. Upon the succeeding cycle of operation of the machine the check strip is fed to a position to be severed by the knives 85 and 86, the severed portion of the strip passing through the chute 127 until arrested by the plate 131 (Figs. 3 and 23) in which position it will be gripped by the clamping plates 1330 and 1335 carried by the check delivering arm 132.
- 60 The rocking of the shafts 32 under control of the clerks' banks of keys 3 will, through intermediate mechanism comprising arms 157, links 158, arms 159 and 162, links 163 and plates 164, adjust the differentially movable selecting slides 169 mounted in the units and tens carriers 171, after which said carriers will be rotated by pawls 177 engaging with ratchets 176 carried by the shafts 175 to which the carriers are connected (Figs. 2, 3, 9, 10, 13 and 14). These adjusted selected members 169 do not come into operative condition until the end of the second cycle of operation of the machine at which time the carrier 171 under the control of the tens bank of clerks' keys 3, is rotated to such an extent by its pawl and ratchet previously described, as to elevate one of the rods 215 into engagement with its respective stud 217 extending downwardly from the driving member 196. As before stated, this coupling of the rod to the driving member occurs at the end of the second cycle of operation of the machine, during which cycle the check is cut off and deposited in the chute 127. This cutting of the check occurs shortly after the beginning of the operation of the machine upon the second cycle and upon the return of the check delivering arm to its normal position, it being understood that such arm is operated more or less on each operation of the machine. The clamping plates 1330 and 1335 of the check delivering arm will clamp the check and hold it ready for delivery to its proper receptacle upon the next or third cycle of operation. Upon this third cycle of operation the driving member 196 having one of the rods 215 coupled thereto, as previously described, will drive the frame 220 (Fig. 14) carrying the coupling rods 215 an extent dependent on which one of the rods is coupled to the driving member 196. The rack plate 223 carried by one of the rods 221 supporting the frame 220 will cause the gear 224 secured to the shaft 133 to be rotated a distance corresponding to the extent of movement imparted to the frame 220 carrying the coupling rods 215. This rocking of the shaft 133 will cause the check delivering arm 132 to be rotated in a clockwise direction (Figs. 15 and 21) to carry the check to the receptacle 141 corresponding to the key of the tens bank of clerks' keys 3 that is depressed.
- 65 The units bank of clerks' keys control the adjustment of one of the differentially movable selecting slides 169 in identically the same way as said slide is controlled by the tens bank of keys. During the succeeding cycle of operation of the machine after the slide has been differentially adjusted under the control of the units bank of keys said slide will be rotated so as to act upon the spirally arranged fingers 286 (Fig. 9) carried by the sleeve 283. By this adjustment of the sleeve 283 carrying the fingers 286 a collar 272 mounted upon the shaft 135 (Fig. 3) will be adjusted upon said shaft corresponding to the adjustment of sleeve 282 carrying the fingers 286 by suitable intermediate mechanism between said sleeve and

the collar 272. This adjustment of the collar 272 occurs during the second cycle of operation of the machine, during which cycle one of the coupling rods 215 is coupled to the driving member for the check delivering arm 132. This adjustment of the collar 272 upon the shaft 135 will through the bell crank 266, adjust the slide 262 (Fig. 21) and through the connection of said slide with the finger 156 adjust the latter upon the shaft 260. Upon the third cycle of operation of the machine the check delivery arm 132 will be adjusted in accordance with the coupling rod 215 connected to the driving member 196 and will carry the actuating finger 156 for determining the compartment of the receptacle in which the check is to be delivered. After the adjustment of the check delivering arm 132 to its proper receptacle the shaft 260 carrying finger 156 will be rocked by the cam disk 302 (Figs. 3 and 15) and intermediate connections comprising the arm 291, link 293, collar 294, lever 297, link 298 and bell crank 299. This rocking of the shaft will cause the finger 156 to engage with the head 155 of one of the rods 154 and lower said rod, by which movement the deflecting plate 150 connected to said rod will be inclined (Fig. 4) so as to direct the check into its proper compartment 149 of the selected receptacle. This rocking of the shaft 260 will cause an arm 325 secured to said shaft to be rocked by which movement the arm 326 will be rocked in a clockwise direction (Fig. 21) through the rod 327 connecting said arm with the arm 325. This movement of the arm 326 will, through a pin 327 carried thereby, cause the arm 139 to be rocked also in a clockwise direction, by which movement the spring 136 will be carried on the opposite side of the pivotal point 140 of the arm 139 from that in which it was shown in Fig. 21, thereby untensioning said spring so that the clamping arm 133 may be rocked about its pivotal point 134 by spring 142, which rocking movement releases the check so that the same may pass down the rear portion of the selected receptacle 141 until it contacts with the plate 150 for deflecting said check into its compartment 149. This release of the clamping plate 133 will cause the spring operated pawl 328 to pass out of the recess 329 formed in said clamping arm and to pass into engagement with the inner edge of said clamping arm, thereby holding said arm in its released position against the tension of the spring 136, which spring has been returned to its normal position as shown in Fig. 21, upon the return of the shaft 260 to its normal position which occurs immediately after the operation of the rod 154.

When the check delivering arm 132 is restored to its normal position the projection 330 extending from the lower portion of the check chute 129 will contact with the pawl

328 at the very last increment of movement of the check delivering arm 132 and rock said pawl against the tension of its spring until the recess 329 formed in the clamping arm 1330 presents itself to the free end of 70 said pawl, at which time the spring 139 will draw the clamping arm in contact with the stationary arm 135 and thereby clamp the check 46 which previously has been deposited upon the arresting plate 131. As the 75 check delivering arm is returned to its normal position the inner edge of the stationary clamping plate 135 will contact with the projection 331 extending downwardly from the door 332 formed upon the lower portion 80 of the check chute 129 and cam said door about its pivotal point 333 so that the check 46 in the lower part of the receptacle of the chute may be clamped by the plates 133 and 135 and withdrawn from said receptacle 85 upon the succeeding operation of the machine. Immediately after the withdrawal of the severed check by the movement of the check delivering arm the door 333 is automatically closed by a suitable spring (not 90 shown) so as to prevent the accidental withdrawal of the check which is deposited in the check chute while the check delivering arm is delivering the previously severed check.

With the above described construction it will be seen that a check containing a record of each sale made by each clerk operating under a particular cashier will be deposited in its appropriate compartment so that at 100 the end of a day's business these assorted checks may be taken out and run through an auditing machine such as disclosed in co-pending application for Letters Patent of the United States No. 723,205 filed by the 105 present applicant, September 30th, 1912, and through the perforated data thereon automatically accumulate the totals of the sales made by the various clerks. These totals with the assorted check arrangement may 110 be more quickly ascertained than with the continuous strip as shown in the last mentioned application, for the reason that with a continuous strip it would be necessary, in order to ascertain any particular clerk's 115 total, to run the whole strip through the machine, which strip contains the sales made by the various clerks operating under a particular cashier, whereas with the present system whereby the record of the sales are 120 sorted automatically, it is only necessary to run the sales made by the particular clerk whose total it is wished to ascertain, through the machine.

Another advantage gained by the automatic assortment of the records of the sales made by the various clerks operating under a cashier is that where it is desired to record only printed data upon the assorted checks the total of the various clerks may be 125 130

quickly ascertained by listing the various sales made by the different clerks upon an adding machine from the data recorded upon the assorted checks thereby avoiding the necessity of manually assorting the sales slips when the latter reach the auditing department in order to ascertain the clerks' totals as is done with the system universally in use at present.

10 While the form of mechanism herein shown and described is admirably adapted to fulfil the objects primarily stated, it is to be understood that it is not intended to confine the invention to the one form of embodiment shown and described herein, as it is susceptible of embodiment in various forms, all coming within the scope of the claims which follow.

What is claimed is:—

20 1. In a machine of the class described, the combination with a plurality of receptacles, of means for feeding a check strip, means for severing the strip into checks, and a differentially movable device for depositing 25 a severed check into any desired receptacle.

2. In a machine of the class described, the combination with a plurality of receptacles, of means for feeding a check strip, means for severing the strip into checks, and a 30 differentially rotatable device for depositing a severed check into any desired receptacle.

3. In a machine of the class described, the combination with a plurality of receptacles, each one being divided into a plurality of 35 compartments, of means for feeding a check strip, means for severing the strip into checks, a differentially movable device for depositing the checks into the various receptacles, and means for selecting the compartments into which the checks are to be deposited.

4. In a machine of the class described, the combination with a plurality of receptacles, each one being divided into a plurality of 45 compartments, of means for feeding a check strip, means for severing the strip into checks, a differentially movable device for delivering the checks to the various receptacles, and means carried by the differential 50 device for selecting the compartments into which the checks are to be deposited.

5. In a machine of the class described, the combination with means for recording suitable data upon a paper strip, of means for 55 feeding the strip to the recording means, mechanism for severing the portion of the strip containing the recorded data, a plurality of receptacles, and a differentially movable member for depositing the severed 60 check into any desired receptacle.

6. In a machine of the class described, the combination with means for recording suitable data upon a paper strip, of means for feeding the strip to the recording means, 65 mechanism for severing the portion of the

strip containing the recorded data, a plurality of receptacles, and a differentially movable member having a device for gripping the severed portion of the strip and depositing it into any desired receptacle.

7. In a machine of the class described, the combination with means for recording suitable data upon a paper strip, of means for feeding the strip to the recording means, mechanism for severing the portion of the 70 strip containing the recorded data, a plurality of receptacles, a differentially movable member having a device for gripping the severed portion of the strip and delivering it to any desired receptacle, and means 75 for operating the gripping device to deposit the severed check in the receptacle.

8. In a machine of the class described, the combination with means for recording suitable data upon a paper strip, of means for feeding the strip to the recording means, mechanism for severing the portion of the strip containing the recorded data, a plurality of receptacles, each having a series of 80 compartments, and a differentially movable 85 member for depositing the severed portion of the strip into any compartment of any receptacle.

9. In a machine of the class described, the combination with means for recording suitable data upon a paper strip, of means for feeding the strip to the recording means, mechanism for severing the portion of the strip containing the recorded data, a plurality of receptacles, each having a series of 90 compartments, and a differentially movable member having a device for gripping the severed portion of the strip and delivering it to any desired compartment of any receptacle.

10. In a machine of the class described, the combination with a plurality of check receptacles, of a differentially movable member for depositing a check into any desired receptacle, and manipulative devices controlling the movement of said member.

11. In a machine of the class described, the combination with a plurality of check receptacles, of a differentially movable member having a device for gripping a check 115 and delivering it to any desired receptacle, and manipulative devices controlling the movement of said member.

12. In a machine of the class described, the combination with a plurality of check 120 receptacles, each having a series of compartments, of a differentially movable member for depositing the check into any desired receptacle, and means for selecting the compartment in which the check is to be deposited.

13. In a machine of the class described, the combination with a plurality of check receptacles, each having a series of compartments, of a differentially movable member 130

for delivering the check to any desired receptacle, and means carried by said member for selecting the compartment in which the check is to be deposited.

5 14. In a machine of the class described, the combination with a plurality of check receptacles, each having a series of compartments, of a differentially movable member for delivering the check to any desired receptacle, a differentially adjustable device carried by said member for selecting the compartment in which the check is to be deposited, and keys for determining the extent of movement of the differential member 10 and the adjustable device carried thereby.

15. In a machine of the class described, the combination with a check receptacle having a plurality of compartments, of a series of deflecting plates for directing the checks 20 to their proper compartments, a differentially adjustable device for actuating the plates, and manipulative devices controlling the adjustment of said device.

16. In a machine of the class described, the combination with a check receptacle having a plurality of compartments, of a series of deflecting plates for directing the checks to their proper compartments, a differentially adjustable device for actuating 30 the plates, a detent for latching the actuated plates, and manipulative devices controlling the adjustment of the differential device.

17. In a machine of the class described, the combination with a check receptacle having a plurality of compartments, of manipulative devices for selecting during one cycle of operation of the machine the compartment in which the check is to be delivered, and means for depositing the check during 40 another cycle of operation of the machine.

18. In a machine of the class described, the combination with a plurality of check receptacles, each having a series of compartments, means for delivering a check to any 45 desired receptacle, manipulative devices controlling the selection of the desired receptacle, a series of deflecting plates for directing the check to its proper compartment in the selected receptacle, a differentially adjustable device for actuating the plates, and a second set of manipulative devices controlling the adjustment of said device.

19. In a machine of the class described, the combination with a plurality of check receptacles, each having a series of compartments, a differentially movable member for delivering a check to any desired receptacle, manipulative devices controlling the movement of said member, a series of deflecting plates for directing the check to its proper compartment in the selected receptacle, a differentially adjustable device carried by the movable member for actuating the plates,

and a second set of manipulative devices controlling the adjustment of said device.

20. In a machine of the class described, the combination with a plurality of check receptacles, of a differentially movable member for delivering a check to any desired 70 receptacle, a driving device for said member, and means for so coupling the member to the driving device whereby said member will be actuated differentially.

21. In a machine of the class described, 75 the combination with a plurality of check receptacles, of a differentially movable member for delivering a check to any desired receptacle, a driving device for said member, a series of rods for coupling the member 80 and driving device whereby said member will be actuated differentially, and means for actuating the rods.

22. In a machine of the class described, the combination with a plurality of check 85 receptacles, of a differentially movable member for delivering a check to any desired receptacle, a driving device for said member, a series of rods normally connected to the differentially movable member, and 90 means for coupling any desired rod to the driving device for the purpose described.

23. In a machine of the class described, the combination with a plurality of check 95 receptacles, of a differentially movable member for delivering a check to any desired receptacle, a driving member for said movable member, a series of rods carried by one of said members, and means for coupling any desired rod to the other member for the 100 purpose described.

24. In a machine of the class described, the combination with a plurality of check receptacles, of a differentially movable member for delivering a check to any desired 105 receptacle, a driving member for said movable member, a series of rods for coupling said members, and a rotatable device for selecting the coupling rod.

25. In a machine of the class described, 110 the combination with a plurality of check receptacles, of a differentially movable member for delivering a check to any desired receptacle, a driving member for said movable member, a series of rods carried by one 115 of the members and normally disconnected from the other member, and a rotatable device for selecting and actuating any desired rod for the purpose of connecting the members.

120 26. In a machine of the class described, the combination with a plurality of check receptacles, of a differentially movable member for delivering a check to any desired receptacle, a driving member for said movable member, a series of rods carried by the differentially movable member, and a rotatable device for selecting and actuating any 125

desired rod for the purpose of connecting said movable member with the driving member.

27. In a machine of the class described, 5 the combination with a plurality of check receptacles, of a differentially movable member for delivering a check to any desired receptacle, a driving member for said movable member, a series of rods for coupling 10 said members, a differentially adjustable device for selecting the rods, and means for rotating said device after it has been adjusted for the purpose of actuating the selected rod to couple said members.

15 28. In a machine of the class described, the combination with a plurality of check receptacles, of a driven member for delivering a check to any desired receptacle, a pivotal driving member for said driven 20 member, a series of rods carried by the driven member and arranged to be connected to the driving member at different points from its fulcrum whereby a differential movement is imparted to the driven 25 member, and means for connecting the rods to the driving member.

29. In a machine of the class described, 30 the combination with a plurality of check receptacles, of a driven member for delivering a check to any desired receptacle, a pivotal driving member for said driven member, a series of rods carried by the driven member and arranged to be connected to the driving member at different 35 points from its fulcrum whereby a differential movement is imparted to the driven member, a differentially adjustable device for selecting the rods, and means for actuating the selecting device after it has been 40 adjusted for the purpose of connecting the selected rod to the driving member.

30. In a machine of the class described, 45 the combination with a plurality of check receptacles, of a driven member for delivering a check to any desired receptacle, a pivotal driving member for said driven member, a series of rods carried by the driven member and arranged to be connected to the driving member at different 50 points from its fulcrum whereby a differential movement is imparted to the driven member, a differentially adjustable device for actuating the rods, a rotatable frame carrying the adjustable device, and means 55 for rotating the frame whereby the adjustable device will actuate the selected rod for the purpose of connecting it to the driving member.

31. In a machine of the class described, 60 the combination with a plurality of check receptacles, each having a plurality of compartments, of a driven member for delivering a check to any desired receptacle, a driving member for the check delivering

member, means for so coupling said members 65 as to impart a differential movement to the driven member by the driving member, a series of deflecting plates for directing the check to its proper compartment in the selected receptacle, and means for operating 70 the deflecting plates.

32. In a machine of the class described, 75 the combination with a plurality of check receptacles, each having a plurality of compartments, of a driven member for delivering a check to any desired receptacle, a driving member for the check delivering member, a series of rods carried by one of said members, means for connecting any desired rod with the other member whereby 80 said driven member will be actuated differentially by the driving member, a series of deflecting plates for directing the check to its proper compartment in the selected receptacle, and means for operating the deflecting plates.

33. In a machine of the class described, 90 the combination with a plurality of check receptacles, each having a plurality of compartments, of a driven member for delivering a check to any desired receptacle, a driving member for the check delivering member, a series of rods connected to the check delivering member, means for selectively connecting the rods to the driving member 95 whereby the driven member will be actuated differentially, a series of deflecting plates for directing the check to its proper compartment in the selected receptacle, and means for operating the deflecting plates. 100

34. In a machine of the class described, 105 the combination with a plurality of check receptacles, each having a plurality of compartments, of a driven member for delivering a check to any desired receptacle, a driving member for the driven member, a series of rods connected to the driven member, means for selectively connecting the rods to the driving member whereby the driven member will be actuated differentially, a series of deflecting plates for directing the check to its proper compartment in the selected receptacle, and means carried 110 by the driven member for operating the deflecting plates. 115

35. In a machine of the class described, 120 the combination with a plurality of check receptacles, each having a plurality of compartments, of a driven member for delivering a check to any desired receptacle, a driving member for the driven member, a series of rods connected to the driven member, means for selectively connecting the rods to the driving member whereby the driven member will be actuated differentially, a series of deflecting plates for directing the check to its proper compartment in the selected receptacle, means carried by the 125

driven member for operating the deflecting plates, and means for latching the plates in their operated position.

36. In a machine of the class described, the combination with a plurality of check receptacles, each having a plurality of compartments, of a driven member for delivering a check to any desired receptacle, a driving member for the driven member, a series of rods connected to the driven member, means for selectively connecting the rods to the driving member whereby the driven member will be actuated differentially, a series of deflecting plates for directing the check to its proper compartment in the selected receptacle, a differentially adjustable device carried by the driven member for operating the deflecting plates, and means controlling the adjustment of said device.

37. In a machine of the class described, the combination with a plurality of check receptacles, each having a plurality of compartments, of a driven member for delivering a check to any desired receptacle, a driving member for the driven member, a series of rods connected to the driven member, means for selectively connecting the rods to the driving member whereby the driven member will be actuated differentially, a series of deflecting plates for directing the check to its proper compartment in the selected receptacle, a differentially adjustable device carried by the driven member for operating the deflecting plates, and a shiftable and rotatable device controlling the adjustment of said device.

38. In a machine of the class described, the combination with a plurality of check receptacles, each having a plurality of compartments, of a driven member for delivering a check to any desired receptacle, a driving member for the driven member, a series of rods connected to the driven member, means for selectively connecting the rods to the driving member whereby the driven member will be actuated differentially, a series of deflecting plates for directing the check to its proper compartment in the selected receptacle, a differentially adjustable device carried by the driven member for operating the deflecting plates, spirally arranged fingers controlling the adjustment of said device, and means for operating the fingers.

39. In a machine of the class described, the combination with a check receptacle divided into a plurality of compartments, of a differentially adjustable device for selecting the compartment in which the check is to be deposited, and spirally arranged fingers controlling the adjustment of said device.

40. In a machine of the class described, the combination with a check receptacle divided into a plurality of compartments, of a

series of deflecting plates for directing the check into any desired compartment, a differentially adjustable device for selecting the compartments, and manipulative devices controlling the adjustment of said device.

41. In a machine of the class described, the combination with a check receptacle divided into a plurality of compartments, of a series of deflecting plates for directing the check into any desired compartment, a differentially adjustable device for actuating the plates, spirally arranged fingers controlling the adjustment of said device, and manipulative devices controlling the operation of the spirally arranged fingers.

42. In a machine of the class described, the combination with a check receptacle divided into a plurality of compartments, of a series of deflecting plates for directing the check into any desired compartment, a differentially adjustable device for actuating the plates, a detent for latching the actuated plates, spirally arranged fingers controlling the differential adjustment of said device, and manipulative devices controlling the operation of the spirally arranged fingers.

43. In a machine of the class described, the combination with a check receptacle divided into a plurality of compartments, of a series of deflecting plates for directing the check into any desired compartment, a differentially adjustable device for actuating the plates, spirally arranged fingers controlling the differential adjustment of said device, and a shiftable and rotatable device for actuating the fingers.

44. In a machine of the class described, the combination with a check receptacle divided into a plurality of compartments, of a series of deflecting plates for directing the check into any desired compartment, a differentially adjustable device for actuating the plates, spirally arranged fingers controlling the differential adjustment of said device, a rotatable frame carrying a differentially adjustable slide for actuating the fingers, and manipulative devices controlling the adjustment of the slide.

45. In a machine of the class described, the combination with means for printing suitable data upon a check, of a plurality of check receptacles, a differentially adjustable device for depositing the printed check into any one of the receptacles, and manipulative devices controlling the adjustment of the check depositing device.

46. In a machine of the class described, the combination with means for printing suitable data upon a check, of a plurality of check receptacles, a differentially adjustable means having a device for gripping the printed check and depositing it into any one of the receptacles, and manipulative devices controlling the adjustment of the check depositing means.

47. In a machine of the class described, the combination with means for printing suitable data upon a check, of a plurality of check receptacles, each having a plurality of compartments, a differentially adjustable device for delivering the printed check to any desired receptacle, means carried by the check delivering device for selecting the compartment of the receptacle in which the check is to be deposited, and manipulative devices controlling the check delivering device and the compartment selecting means.
48. In a machine of the class described, the combination with means for printing suitable data upon a check, of a plurality of check receptacles, each having a plurality of compartments, a differentially adjustable device for delivering the printed check to any desired receptacle, a differentially adjustable member carried by the check delivering device for selecting the compartment of the receptacle in which the check is to be deposited, and manipulative devices controlling the adjustment of the check delivering device and the compartment selecting member.
49. In a machine of the class described, the combination with means for printing suitable data upon a check, of a receptacle divided into a plurality of compartments, a series of deflecting plates for directing the printed check to its proper compartment, a differentially adjustable member for actuating the plates, and manipulative devices controlling the adjustment of said member.
50. In a machine of the class described, the combination with means for printing suitable data upon a check, of a receptacle divided into a plurality of compartments, a series of deflecting plates for directing the printed check to its proper compartment, a differentially adjustable member for actuating the plates, manipulative means controlling the adjustment of said member, and means for latching the actuated plates.
51. In a machine of the class described, the combination with means for perforating suitable data upon a check, of a plurality of check receptacles, a differentially adjustable device for depositing the perforated check into any one of the receptacles, and manipulative devices controlling the adjustment of the check depositing device.
52. In a machine of the class described, the combination with means for perforating suitable data upon a check, of a plurality of check receptacles, a differentially adjustable means having a device for gripping the perforated check and depositing it into any one of the receptacles, and manipulative devices controlling the adjustment of the check depositing means.
53. In a machine of the class described, the combination with means for perforating suitable data upon a check, of a plurality of check receptacles, each having a plurality of compartments, a differentially adjustable device for delivering the perforated check to any desired receptacle, means carried by the check delivering device for selecting the compartment of the receptacle in which the check is to be deposited, and manipulative devices controlling the check delivering device and the compartment selecting means.
54. In a machine of the class described, the combination with means for perforating suitable data upon a check, of a plurality of check receptacles, each having a plurality of compartments, a differentially adjustable device for delivering the perforated check to any desired receptacle, a differentially adjustable member carried by the check delivering device for selecting the compartment of the receptacle in which the check is to be deposited, and manipulative devices controlling the adjustment of the check delivering device and the compartment selecting member.
55. In a machine of the class described, the combination with means for perforating suitable data upon a check, of a receptacle divided into a plurality of compartments, a series of deflecting plates for directing the perforated check to its proper compartment, a differentially adjustable member for actuating the plates, and manipulative devices controlling the adjustment of said member.
56. In a machine of the class described, the combination with means for perforating suitable data upon a check, of a receptacle divided into a plurality of compartments, a series of deflecting plates for directing the perforated check to its proper compartment, a differentially adjustable member for actuating the plates, a manipulative device controlling the adjustment of said member, and means for latching the actuated plates.
57. In a machine of the class described, the combination with means for perforating suitable data upon a paper strip, of means for feeding the strip to the perforating means, mechanism for severing the portion of the strip containing the perforated data, a plurality of receptacles, and a differentially movable member for depositing the severed check into any desired receptacle.
58. In a machine of the class described, the combination with means for perforating suitable data upon a paper strip, of means for feeding the strip to the perforating means, mechanism for severing the portion of the strip containing the perforated data, a plurality of receptacles, and a differentially movable member having a device for gripping the severed portion of the strip and delivering it to any desired receptacle.
59. In a machine of the class described, the combination with means for perforating suitable data upon a paper strip, of means for feeding the strip to the perforating

means, mechanism for severing the portion of the strip containing the perforated data, a plurality of receptacles, a differentially movable member having a device for gripping the severed portion of the strip and delivering it to any desired receptacle, and means for operating the gripping device to deposit the severed check in the receptacle.

60. In a machine of the class described, 10 the combination with means for perforating suitable data upon a paper strip, of means for feeding the strip to the perforating means, mechanism for severing the portion of the strip containing the perforated data, 15 a plurality of receptacles, each having a series of compartments, and a differentially movable member for depositing the severed portion of the strip into any compartment of any receptacle.
61. In a machine of the class described, 20 the combination with means for perforating suitable data upon a paper strip, of means for feeding the strip to the perforating means, mechanism for severing the portion 25 of the strip containing the perforated data, a plurality of receptacles, each having a series of compartments, and a differentially movable member having a device for gripping the severed portion of the strip and 30 delivering it to any desired compartment of any receptacle.

62. In a machine of the class described, 35 the combination with means for printing suitable data upon a paper strip, of means for perforating the strip with characters symbolical of the printed data, mechanism for feeding the strip from one of said means to the other, means for severing the portion of the strip containing the printed and perforated data, a plurality of receptacles each 40 having a series of compartments, a differentially movable member for depositing the severed portion of the strip into any desired receptacle, and means for directing the 45 severed check to the proper compartment of the selected receptacle.

63. In a machine of the class described, the combination with means for printing suitable data upon a paper strip, of means for 50 perforating the strip with characters symbolical of the printed data, mechanism for feeding the strip from one of said means to the other, means for severing the portion of the strip containing the printed and perforated data, a plurality of receptacles each 55 having a series of compartments, a differentially movable member for delivering the severed portion of the strip to any desired receptacle, and means carried by the delivering member for selecting the compartment 60 in which the severed portion of the strip is to be deposited.

64. In a machine of the class described, the combination with a plurality of check 65 receptacles, of a differentially movable mem-

ber for delivering a check to any desired receptacle, an adjustable element controlling the movement of said member, and manipulative devices controlling the adjustment of said element.

70

65. In a machine of the class described, the combination with a plurality of check receptacles, of a differentially movable member for delivering a check to any desired receptacle, an adjustable element controlling the movement of said member, manipulative devices controlling the adjustment of said element, a frame carrying the adjustable element, and means for rotating the frame for the purpose described.

80

66. In a machine of the class described, the combination with a check receptacle divided into a plurality of compartments, of a differentially adjustable member controlling the selection of the compartment in which the check is to be delivered, spirally arranged fingers controlling the adjustment of said member, and key controlled means for actuating the fingers.

67. In a machine of the class described, the combination with a check receptacle divided into a plurality of compartments, of a differentially movable member controlling the selection of the compartment in which the check is to be delivered, spirally arranged fingers controlling the movement of said member, an adjustable element arranged to be brought into coöperative relation with any one of said fingers for the purpose described and manipulative means controlling the adjustment of said element.

68. In a machine of the class described, the combination with a plurality of check receptacles, each having a series of compartments, of a differentially movable member for delivering a check to any desired receptacle, an adjustable element controlling the movement of said member, a series of keys controlling the adjustment of said element, an adjustable device carried by the movable member for selecting the department in which the check is to be delivered, spirally arranged fingers controlling the adjustment of said device, a second adjustable element arranged to be brought into coöperative relation with any one of said fingers, and a second series of keys controlling the adjustment of the last mentioned element.

69. In a machine of the class described, the combination with means for recording 120 suitable data upon a paper strip during one cycle of operation of the machine, of means for severing the portion of the strip containing the recorded data upon a second cycle of operation of the machine, a plurality of 125 receptacles, and means for delivering the severed portion of the strip to any one of the receptacles upon a third cycle of operation of the machine.

70. In a machine of the class described,

130

the combination with means for recording suitable data upon a paper strip, of means for severing the portion of the strip containing the recorded data, a plurality of receptacles, means for delivering the severed portion of the strip to any desired receptacle, and an operating mechanism common to the recording means, severing means and delivering means and so constructed as to sever and deliver said severed portion of the strip upon subsequent cycles of operation of the operating mechanism from that in which the recording means is operated.

71. In a machine of the class described, the combination with means for recording suitable data upon a paper strip, of means for severing the portion of the strip containing the recorded data, a plurality of receptacles, means for delivering the severed portion of the strip to any desired receptacle, and an operating mechanism common to the severing and delivering means and so constructed as to deliver the severed portion of the strip to its proper receptacle upon a subsequent cycle of operation of the operating mechanism from that in which the severing means is operated.

72. In a machine of the class described, the combination with means for recording suitable data upon a paper strip, of means for severing the portion of the strip containing the recorded data, a plurality of receptacles, means for delivering the severed portion of the strip to any desired receptacle, an adjustable device controlling the selection of the receptacle, and means for adjusting said device during the cycle of operation of the machine in which the recording means is actuated, which device becomes operative for controlling the selection of a receptacle at a subsequent cycle of operation of the machine.

73. In a machine of the class described, the combination with means for perforating suitable data upon a paper strip during one cycle of operation of the machine, of means for severing the portion of the strip containing the perforated data upon a second cycle of operation of the machine, a plurality of receptacles, and means for delivering the severed portion of the strip to any one of the receptacles, and means for delivering the severed portion of the strip to any one of the receptacles upon a third cycle of operation of the machine.

74. In a machine of the class described, the combination with means for perforating suitable data upon a paper strip, of means for severing the portion of the strip containing the perforated data, a plurality of receptacles, means for delivering the severed portion of the strip to any desired receptacle, and an operating mechanism common to the perforating means, severing means and delivering means and so constructed as to sever and deliver said severed portion of the

strip upon subsequent cycles of operation of the operating mechanism from that in which the perforating means is operated.

75. In a machine of the class described, the combination with means for perforating suitable data upon a paper strip, of means for severing the portion of the strip containing the perforated data, a plurality of receptacles, means for delivering the severed portion of the strip to any desired receptacle, and an operating mechanism common to the severing and delivering means and so constructed as to deliver the severed portion of the strip to its proper receptacle upon a subsequent cycle of operation of the operating mechanism from that in which the severing means is operated.

76. In a machine of the class described, the combination with means for perforating suitable data upon a paper strip, of means for severing the portion of the strip containing the perforated data, a plurality of receptacles, means for delivering the severed portion of the strip to any desired receptacle, an adjustable device controlling the selection of the receptacle, and means for adjusting said device during the cycle of operation of the machine in which the perforating means is actuated, which device becomes operative for controlling the selection of a receptacle at a subsequent cycle of operation of the machine.

77. In a machine of the class described, the combination with means for printing suitable data upon a paper strip, of means for perforating the strip with characters symbolical of the printed data, mechanism for feeding the strip from one of said means to the other, means for severing the portion of the strip containing the printed and perforated data, a plurality of receptacles, mechanism for depositing the severed portion of the strip into any receptacle, and an operating mechanism common to the various means and mechanisms recited herein and so constructed that the severing means and depositing mechanisms for the paper strip are not operated until subsequent cycles of operation of the operating mechanism from that cycle in which the printing and perforating means are operated.

78. In a machine of the class described, the combination with means for printing suitable data upon a paper strip, of means for perforating the strip with characters symbolical of the printed data, means for severing the portion of the strip containing the printed and perforated data, a plurality of receptacles, mechanism for depositing the severed portion of the strip into any receptacle, an adjustable device controlling the selection of the receptacle, and means for adjusting said device during the cycle of operation of the machine in which the printing and the perforating means are actuated,

which device becomes operative for controlling the selection of a receptacle at a subsequent cycle of operation of the machine.

5 79. In a machine of the class described, the combination with receptive means having a plurality of compartments, of a device having two differential adjustments at each operation thereof for selecting any 10 desired compartment to which a check is to be delivered.

80. In a machine of the class described, the combination with receptive means having a plurality of compartments, of a device 15 having two differential adjustments, for selecting any desired compartment to which a check is to be delivered, and having an invariable movement to cause the check to be delivered therein, means for controlling said 20 differential adjustments of said device, and means for giving the latter its invariable movement.

81. In a machine of the class described, the combination with receptive means having 25 a plurality of compartments, of a device having two differential adjustments at each operation thereof for selecting any desired compartment to which a check is to be delivered, and two classes of manipulative 30 means, the means of each class being adapted to control a corresponding one of said adjustments.

82. In a machine of the class described, the combination with receptive means having 25 a plurality of compartments, of a device having two differential adjustments at each operation thereof for selecting any desired compartment to which a check is to be delivered, and two independent means

Copies of this patent may be obtained for five cents each, by addressing the "Commissioner of Patents,
Washington, D. C."

each of which controls a corresponding one 40 of said adjustments.

83. In a machine of the class described, the combination with a check receptacle, having a plurality of compartments, of a series of deflecting plates for directing the 45 checks into the desired compartments and normally out of deflecting position, and a device having a differential adjustment for selecting the desired plate to be moved into deflecting position and a movement of invariable extent for moving said plate into 50 such position.

84. In a machine of the class described, the combination with a receptacle having a plurality of check compartments, of a plurality 55 of deflecting plates, one for each compartment, and two sets of manipulative devices for selecting any desired one of said plates for operation.

85. In a machine of the class described, 60 the combination with a main operating mechanism, of a plurality of receptacles, each being divided into a plurality of compartments, a differentially movable device operated by the main operating mechanism for 65 delivering checks to the various receptacles, means for determining the compartments into which the checks are to be deposited, manipulative means for controlling the differentially movable device and the determining means. 70

In testimony whereof I affix my signature in the presence of two witnesses.

FRED M. CARROLL.
